GRAIN ELEVATOR

Charles E. Kaesler, Syracuse, Kans.

Application November 27, 1944, Serial No. 565,361

6 Claims. (Cl. 198—213)

My present invention, in its broad aspect, relates to improvements in grain elevators of the type employing a screw conveyor, and more particularly, it is my purpose to provide an elevator which is capable of wide adjustment to meet varying conditions of practice, and wherein the motor drive is maintained in a vertical position irrespective of the position and inclination of the elevator. My elevator is supported on a vertically adjustable tripod which may be readily moved about and which carries a mounting for a small air-cooled motor which is adjustable to be normally maintained in a vertical, normal position irrespective of the inclination or position of the elevator. The means for mounting the elevator on the tripod permits of pivotal movement of the elevator so that the angle of the elevator may be changed at will, its height regulated, and the position of the elevator otherwise adjusted to effectively meet all requirements of practice.

I also provide novel means for driving the screw conveyor from the motor, which means includes a drive pulley on the conveyor shaft adjacent adjustable idlers, with a belt drive running from the motor over the idlers and drive pulley to give the proper impulse irrespective of the position, inclination, or load imposed on the conveyor. In addition to the above, I provide an improved mounting bracket for the conveyor and motor, and improved intake and exhaust means for the conveyor, whereby an apparatus is attained which is capable of performing work ordinarily requiring much more complicated equipment. To that end, my device is simple in construction, sturdy, practical, and has no fragile or concealed parts likely to become broken or rearranged or out of order.

Other and equally important objects and advantages of my invention will be apparent from the following description and accompanying drawings, but changes may be made in the form, size, shape, arrangement and construction of parts to meet practical requirements provided such changes fall within the purview of my broad inventive concept, and the scope of the appended claims.

In the drawings wherein I have illustrated a preferred form of my invention:

Figure 1 is a side elevation of my invention;

Figure 2 is a sectional side elevation;

Figure 3 is a transverse section taken on the line 3—3 of Figure 2 and shows the pivotal mounting of the conveyor and engine supporting bracket;

Figure 4 is a sectional top plan view of the tripod on the line 4—4 of Figure 3.

Figure 5 is a detail view of an idler and the drive pulley and belt connection;

Figure 6 is a transverse section looking forward toward the drive pulley and idlers, and the bracket mounting for the same.

Figure 7 is a bottom end view showing the journal plate for the screw conveyor shaft;

Figure 8 is a detail of the semi-circular engine saddle and adjustment;

Figure 9 is a longitudinal section partially fragmentary of the engine and conveyor bracket and connections;

Figure 10 is a section on the line 10—10 of Figure 9;

Figure 11 is a longitudinal section through the upper end of the conveyor and the pulley mounting; and

Figure 12 is a section on the line 12—12 of Figure 11.

In the drawings wherein like characters of reference are used to designate like or similar parts throughout the several views;

The numeral 1 designates the supporting tripod for my conveyor and engine, and is formed with legs 2 having pointed ends 3 for insuring a firm ground engagement, and connecting bars 4 for the legs. The legs radiate from a tubular standard 5 in which is slidably mounted a supporting standard 6. Standard 6 has a series of vertically spaced apart openings 7 through which a cotter pin 8 is adapted to be engaged to adjust the height of the standard 6. At the top of the standard is a U-shaped, or forked support 9 having a collar 10 at its lower end fixed on the end of standard 6. The upper ends of the arms 11 of the yoke or U-shaped support 9 are provided with bearing elements 12 supporting a shaft 13, which is prevented from sliding movement which might disengage it from the yoke by cotter pins 14. Mounted for movement on the shaft 13 is a screw conveyor and engine supporting bracket generally designated by 15.

The bracket 15 has a depending, split cylindrical portion 16 the adjacent edges of which are flanged as at 17 and connected by bolts 18 to affect clamping engagement about the elongated tubular screw conveyor casing 19. A web portion 20 connects the portion 16 with a semi-circular saddle 21 which has lateral ears thereon carrying wing nut and bolt clamping assemblies 22 for adjustably clamping a semi-circular engine supporting plate 23 thereon. Plate 23 has a flat platform 24 on which the small air-cooled ore or gasoline

20 connects the portion 16 with a semi-circular saddle 21 which has lateral ears thereon carrying wing nut and bolt clamping assemblies 22 for adjustably clamping a semi-circular engine supporting plate 23 thereon. Plate 23 has a flat platform 24 on which the small air-cooled ore or gasoline

motor 25 is bolted as at 26. The shaft 13 is engaged by the bracket through the web at the upper edge as is shown in Figures 1 and 2, and the screw conveyor casing 19 is clamped into the part 16 at a point somewhat above a point midway its ends whereby it is partly off-center to normally be disposed in the position shown in Figures 1 and 2, but not so much off-center that its angle of inclination cannot be easily adjusted simply by raising or lowering its lower end. The motor is normally maintained in a vertical position irrespective of the inclination of the screw conveyor casing by simply adjusting the semi-circular supporting plate 23 with reference to the saddle 21 through the instrumentality of wing nut and bolt clamping assemblies 22. Bolted into the lower end of the screw conveyor casing 19 is a bearing plate 25a which also serves as a closure and which has a bear 26a thereon. The top of plate 25a is squared off as at 26b. At the upper and opposite end of casing 19 is a bracket generally designated by 27 which carries a bearing 28, and between and mounted in the bearings 26 and 28 is a shaft 29 carrying the screw conveyor 30. The top wall of the lower end of the casing 19 is broken away as at 31 to provide an inlet opening 32 so that in effect the lower part of the casing constitutes a receiving hopper for the grain to be elevated.

Adjacent the upper end of the casing is an outlet opening 33 formed in the lower wall and having lateral depending flange portions 34 to which is pivotally mounted as at 35 a discharge chute 36.

The bracket 27 at the upper end of the casing has a split cylindrical body 37 the edges of which are flanged as at 38 and clamped together by a wing nut and bolt assembly 39 about the end of the casing; the closed end 40 of the body carries the bearing 26 for shaft 29.

The shaft 29 extends through bearing 28 and has mounted thereon a drive pulley 41, and the bracket body 37 has opposed flanges 40a, connected by a semi-circular web 42, on which are adjustably mounted the supports 43 for idler pulleys 44. A V-belt 45 (or other suitable belt device) is trained about the engine drive pulley 45a and about idlers 44 and shaft drive pulley 41 to drive the shaft 29 to rotate the screw conveyor 30 and it will be noted that adjustability is provided to properly position the belt irrespective of the angle of inclination of the conveyor.

A suitable roller bearing assembly 46 (of the Timkin bearing type) is provided at the end of the shaft 29, and is carried in a bearing collar 47 on the closed end 40 of the bracket 27 to anti-frictionally support the shaft, and as shown in Figure 11, a stub shaft 48 may be bolted as at 49 into an opening in the end of shaft 29 to carry the shaft drive pulley 41 thereby to facilitate disassembling the same.

From the foregoing, it will be noted that the height of the supporting standard may be adjusted; that the engine may be kept in a proper vertical position; that the angle of the conveyor may be adjusted, and that it may be swung about the standard to different positions. It is also to be noted that both brackets are of the clamping

type and are removable and adjustable, and that the device as a whole is simple, practical and efficient, and that to operate it, all that is necessary is to start the motor and pour the grain into the lower end whereupon it will be elevated by the screw conveyor and discharged through the chute into a truck or to any other receptacle desired.

From the foregoing, it is believed that the operation and advantages of my invention will be apparent, but it is again emphasized that interpretation thereof should only be conclusive when made in the light of the subjoined claims.

I claim:

15. A grain elevator, comprising a conveyor, a conveyor housing, a vertically adjustable support for said housing, a pivotally mounted bracket on said support clamped to said housing, a supporting saddle on said bracket above the housing, an adjustable engine supporting plate on said saddle, said conveyor having a drive shaft, a bracket on the end of the conveyor housing having a bearing for said drive shaft, a drive pulley on said shaft having an operative connection with the engine, 20 and idler pulleys over which said connection travels to engage said drive pulley.
20. A grain elevator of the screw conveyor type, comprising a conveyor casing having a screw conveyor carrying shaft rotatably mounted therein, 25 a tripod support for said casing having a vertically adjustable standard, a forked yoke on said standard, a bracket pivoted in said yoke and having clamping connection with said casing, a semi-circular saddle on the bracket, a semi-circular engine supporting plate adjustably mounted on the saddle, a bracket device clamped to the end of the conveyor casing and having a closure wall closing the end of the conveyor casing, a drive pulley on the conveyor shaft, idler pulleys 30 adjustably mounted on the bracket adjacent the drive pulley, and a belt drive connection from the engine passing over the idlers and about the drive pulley.
30. The invention as described in claim 2, wherein in said pulley bracket carries an anti-frictional roller bearing mounted for the end of the conveyor shaft, and wherein the axes of the idler pulleys are normally substantially at right angles 35 to the axis of the drive pulley.
35. The invention as described in claim 2, wherein in the semi-circular engine supporting plate has a straight platform supporting an engine, and wherein clamping nut and bolt members are provided between the semi-circular saddle and plate to adjust the plate thereto.
40. The invention as described in claim 2 where- 40 in the pulley bracket has lateral flanges connected by a web, and the idler pulleys are mounted on 45 flanges adjacent to but in a different plane than the shaft drive pulley.
45. The invention as described in claim 2, where- 45 in the pivotal connection between the bracket and the yoke on the vertical standard is off-center, and wherein the conveyor casing is clamped in 50 the bracket at a point above the midway point between the ends of the casing.

CHARLES E. KAESLER.
